UNITED STATES PATENT OFFICE.

JOHN W. MILLER, OF MUSCATINE, IOWA, ASSIGNOR TO THE MCKEE AND BLIVEN
BUTTON COMPANY, OF MUSCATINE, IOWA, A PARTNERSHIP.

BUTTON-MACHINE.

947,995.

Specification of Letters Patent. Patented Feb. 1, 1910.

Application filed April 12, 1906. Serial No. 311,345.

To all whom it may concern:

Be it known that I, JOHN W. MILLER, of Muscatine, in the county of Muscatine and State of Iowa, have invented certain new and useful Improvements in Button-Machines; and I hereby declare that the following is a full, clear, and exact description thereof, reference being had to the accompanying drawings, which form part of this specification.

10 This invention is an improvement in machines for cutting blanks from fragile material by means of tubular saws; being particularly designed for use in shell pearl-button making to facilitate the sawing out of disks or button blanks from the pearl or mussel shells, and to do away with the necessity for the workman holding the shell by hand or with tongs, as is now ordinarily done, 15 by providing mechanism by which the shells can be held during the cutting operation; the operator merely having to position the shell on the holder preparatory to the sawing of a blank from the shell; and after each blank 20 is cut he can shift the shell so that an uncut portion thereof will be presented to the saw.

25 The principal objects of the invention are to provide an improved shell-holder by which the shell is properly held and presented to the saw during the cutting operation. Second, to provide a shell-holder which will automatically adjust itself to the variations in size and curvatures of the shell, and hold the same positively and securely during the 30 cutting operations whether it be thick or thin, regular or irregular in contour, so that the pearl face of the shell will be presented flat to the saw, and the cut blanks will have their edges perpendicular to the pearl face, notwithstanding irregularity or unevenness 35 of the shell; and when such blanks are reduced to proper thickness they will be perfect, instead of being beveled or slanted on the edges, as are so many hand-cut blanks, 40 and which defect greatly lessens the value of the blanks and sometimes renders them 45 worthless.

50 Further objects of the invention are third—to provide a shell-holder in which the shell can be placed, adjusted, and removed, with greatest ease; fourth—to cause the saw to operate on the shell held by such holder with precision and certainty, yet without undue pressure; fifth—to enable the shell-holder and saw to travel together during 55

the cutting operation; and sixth—to arrange a number of holders and relative cutters in an endless series, and cause the whole series to travel, preferably continuously, so that each holder will be brought up to the operator in its turn, can have a shell properly located thereon, and then move on during the cutting operation, while the other holders are similarly manipulated in succession; thus enabling one operator to attend to a number of blank-holders and cutters without losing any time during the cutting operations, which are performed automatically by the machine during the travel of the holders and cutters.

70 Still further objects of the invention are seventh—to provide means for supplying water to the interior of the tubular saws during the cutting operations, thereby facilitating the cutting operation, preserving the 75 temper of the saws, and prolonging their usefulness. Eighth—to provide means for ejecting the cut blanks from the saws at the proper point, the water supplying devices being preferably used as part of the means 80 for ejecting the blanks; and ninth—to provide means for automatically detaching the saws, when it becomes desirable to replace them.

85 The invention will be clearly understood from the following description of the machine illustrated in the drawings, which has a number of duplicate sets of shell holding and cutting devices arranged to move in an endless path; but it should be understood 90 that the invention is not restricted to any particular number of such mechanisms; and many of the substantial novel features of the invention could be usefully employed in a machine operating on but one shell at a 95 time; and in various constructions of machines; and I therefore refer to the several claims for concise summaries of the essential features, parts, and combinations of elements, which are embraced in the invention, 100 and for which protection is desired herein. Furthermore, while I have referred more particularly to "shells" as the objects operated upon, the invention is not restricted to use with shells, and such term is used 105 merely for convenience in explanation, and not as limiting the invention.

110 In the drawings—Figure 1 is a sectional elevation of a complete machine. Fig. 2 is an enlarged view of the self-adjusting shell

support and lower part of clamp. Fig. 3 is an enlarged sectional view of the self-adjusting member of the shell clamp. Fig. 4 is an enlarged sectional elevation of one of the cutting mechanisms showing it in shell receiving position in full lines, and in cutting position, in dotted lines. Fig. 5 is a plan view of the machine. Fig. 6 is an enlarged sectional elevation of the cutting mechanism. Fig. 7 is a top plan view of the machine. Fig. 8 is an enlarged plan view of the self-adjusting or bearing member of the shell-holder, and its supports. Fig. 9 is a diagrammatic view illustrating the cutting operations and the controlling cams. Fig. 10 is a detail view illustrating the saw ejecting operation.

In the embodiment of the invention illustrated in the drawings, the machine has a central shaft 1, which is preferably arranged in a vertical position and has its lower end supported in a step-bearing 1^a in the lower-spider or plate 1^b of the main-frame, and its upper part journaled in a bearing 1^c in the upper spider or plate 1^d of the main-frame, said spiders 1^b, 1^d, being rigidly connected by vertical rods 1^e as shown, although the particular construction of the frame-work of the machine is not a material feature of the invention.

The shaft 1 can be rotated at a slow speed by suitable gearing. As shown a worm-gear 1^f on shaft 1 meshes with a worm 1^g on a counter-shaft 1^h suitably journaled and supported on the main-frame, and provided with a pulley 1ⁱ which can be belted to any suitable driver, not shown. On this shaft 1 between the bearings are fixedly secured a lower disk or plate 3, and an upper disk or plate 4, upon and between which disks the several sets of blank-cutting devices are mounted. These blank cutting devices are all similar in construction and a detailed explanation of one, applies to all, similar parts being similarly numbered in the drawings. Extending vertically between and through the disks 3, 4, is a longitudinally movable rod 5, the lower part of which is confined in a sleeve or guide 3^a on disk 3, while its upper end is guided in a vertically adjustable sleeve 4^a, tapped into an opening in disk 4,—the rod 5 being free to move vertically through the disks.

Attached to rod 5 just above disk 3, is a bracket 6 which has an inwardly projecting portion 6^a, provided with a vertical slot loosely embracing a vertical guide-pin 3^b, beside and parallel with rod 5, to prevent the bracket 6 swinging or turning laterally. Bracket 6 projects beyond the periphery of disk 3, and is provided with an opening 6^b, in which is hung a short cylinder 7, preferably by means of radially projecting pins 7^a, carrying friction rollers 7^b, engaging inclined cam-slots 6^d in the walls of bracket 6 ad-

acent the cylinder, so that if the cylinder is turned in one direction, the rollers will ride up on the cam-slots and lift the cylinder, and if turned in the other direction they will ride down and lower the cylinder 7. The cylinder may be readily turned, by means of a handle 7^c, or any other desired means may be used.

The cylinder 7 supports the self-adjusting bearing member 8 of the shell-holder, which member has a parti-globular or conical head 8^a slightly larger in diameter than the bore of the cylinder, and a depending stem 8^b, smaller than the bore of the cylinder, so that when the bearing member is placed within the cylinder, as shown in Fig. 2, it can oscillate in any direction, owing to the curvature of its head, which practically forms a ball-and-socket joint with the upper end of the cylinder and allows the bearing member to have an almost universal motion, or tilt in any direction. To facilitate this self-adjusting tilting function of the bearing member, I preferably provide antifriction ball-bearings 7^e at the upper end of cylinder 7, and bearing against and sustaining the head of the bearing member as shown in Figs. 2 and 8. These balls 7^e may be confined in position (while free to rotate) by a ring 7^f, as shown.

The bearing member is hollow, and a plug 8^g of wood or other suitable material is placed therein, to form a non-metallic contact surface opposed to the saw, hereinafter referred to; this plug can be pushed out, as worn, by means of a follower 8^h, actuated by a screw 8^g tapped through the lower end of the shank of the bearing-member, as shown.

Upon the rod 5, above bracket 6, is a loose sleeve 9, which is provided with an inwardly extending arm 9^a having a slot engaging the guide 3^b, to prevent the sleeve turning on the rod 5, or relatively to the bracket 6; and sleeve 9 has an outwardly extending arm 9^b provided with an opening surrounded on its lower side by a depending tubular clamp-member 9^c, which is preferably ratchet-toothed on its lower edge as at 9^d, and is adapted to bear upon the top surface of a shell S, or other piece of material, inserted between the clamp-member 9^c, and bearing member 8, as shown in Fig. 4.

The sleeve 9, and attached parts are moved toward bracket 6 by gravity which may be supplemented by a helical spring 5^e strung on rod 5 between the upper end of sleeve 9 and the lower end of the adjustable sleeve-nut 4^a, the pressure of the spring being regulable by turning the sleeve-nut 4^a.

The sleeve may be raised on rod 5, when desired, by means of a hand-lever 9^f, pivoted at 9^g upon a hanger or bracket 4^h depending from disk 4, the outer end of the lever being provided with a hand-piece 9ⁱ, and its inner end being pivotally connected by a

link 9^a to the sleeve, as indicated in Fig. 4, so that when the hand-lever is oscillated by a pull on its hand-piece the sleeve will be raised and the clamping-member 9^c will be separated from the bearing-member 8^a.

When the clamp 9^c is separated from the bearing-member 8^a, a shell S can be easily placed on or removed from the bearing-member, or can be shifted thereon to suit the will of the operator; and when a shell is properly adjusted on the bearing-member, the sleeve 9 is lowered so as to cause clamp 9^c to bite the shell against the bearing-member, and if there is any inequality in the surfaces of the shell, the bearing-member tilts or oscillates so that the clamp gets a firm bite on the shell, and holds it securely, by reason of the weight of the sleeve 9 and the pressure of spring 5^a. After a shell is thus clamped, it is ready to be operated on by the cutter, which is brought into contact with the shell by introducing it through the hollow clamp. In the machine shown the holder is bodily moved so as to present the shell to the tubular saw or cutter, by moving rod 5, (which carries all parts of the clamp), longitudinally,—(raising it vertically in the specific arrangement of parts shown in the drawings.) This movement of the rod and holder being accomplished by means of a cam-plate or ring 5^a, arranged beneath the disk 3, and in and along the path circumscribed by the lower end of rod 5 as it is moved by the rotating disks 3 and 4; said rod 5 having a friction roller 5^c on its lower end bearing on the cam or track 5^a. This track 5^a has a cam-part 5^f adapted to move the rod upward so as to gradually but steadily present the shell held by the holder to the saw, and cause the latter to cleanly cut the blank therefrom; then it has a declining portion 5^e which permits the holder to descend clear of the saw, (by gravity and the action of the spring 5^e). The cam-track need only extend along so much of the path traversed by the holders as is necessary to secure the proper presentation of the shells to the cutter,—the holder remaining in its lowermost position during the remainder of its orbital movement, during which time it passes the point where the operator can adjust the shell for another cut, or remove it and replace a new shell in the holder.

Axially in line with, and opposite each shell-holder, is a rotatable cutting device, comprising a tubular saw, a rotatable spindle carrying the saw, and means for rotating and adjusting the saw. As shown the tubular saw 10 see Fig. 6 is preferably tapered on its upper end, as at 10^a to wedge into the lower internally tapered end 11^a of a socket piece 11^b screwed into the lower end of a tubular spindle 11, which is rotatably journaled in a sleeve 12 secured in a tubular

housing 13 attached to the upper disk 4, and through slots in which disk the spindle and sleeve depend, as shown.

The housing 13 is provided with laterally projecting slotted ears 13^a, transfixed by bolts 13^b tapped into disk 4, so as to secure the cutting devices in position thereon. The spindle 11 has a collar 11^d on its lower end bearing against the lower end of the inclosing sleeve 12, and on its upper end is fastened a small pinion 11^e by means of a set-screw 11^f, or other convenient device, so that the spindle has no longitudinal play in the sleeve, although free to rotate therein.

The lower part of sleeve 12, is exteriorly coarsely threaded as at 12^a, and a hand-nut 12^b is run thereon; this nut rests upon a hanger or bracket 4^m attached to the underside of disk 4, so as to uphold the sleeve and spindle, and by rotating hand-nut 12^b, the sleeve, spindle, saw and pinion are vertically adjusted so as to position the saw 10 properly above the shell-holder, and also to compensate for wear on the saw.

The pinion 11^e meshes with a master-gear 14, loosely journaled on shaft 1 above disk 4 as shown, said master-gear being fast to a concentrically disposed bevel gear 14^a, which meshes with a bevel pinion 14^b on a counter shaft 14^c suitably journaled on the main-frame, and provided with a pulley 14^d which can be belted to any suitable driver, so as to rotate the gear 14 more rapidly than shaft 1.

Within the spindle 11 is an ejector-rod 15, the lower end 15^a of which is slightly reduced in diameter and fitted easily within the cylindrical bore of the tapered shank of the saw. Above the upper end of the saw, the ejector-rod is shouldered as at 15^b. The ejector-rod projects above the spindle and pinion, and has a rounded upper end 15^c which is adapted to travel beneath a cam-plate 16 attached to the frame above the cutters, and in the path circumscribed by the upper ends of the ejectors, and is provided at the proper point with a cam-portion 16^a, which causes the ejectors to move down and eject the button-blank from the saw, as indicated in Fig. 9. The ejector rods however are normally pressed upward by means of helical springs 15^d interposed between their enlarged upper ends and the upper ends of the spindles. The ejector rods are also utilized to throw out the saws when it is desired to renew or replace them; to do which a cam 16^e may be attached to the cam-plate 16, at the proper point, and as the cutter moves thereunder, the cam 16^e depresses the ejector so far that its shoulder 15^b strikes the inner end of the saw and forces it down and out, see Fig. 10. Thus all the saws may be removed and replaced during one rotation of shaft 1, the cam 16^e being thrown out of action as soon as the desired saws are ejected. The ejectors are also utilized as part of the

means for wetting the saws, and for this purpose they are provided with a water-channel 15^e leading from a nipple 15^h, attached to the upper end thereof as shown in Figs. 1, 4 and 6, down to an outlet-port 15^f, in the side of part 15^a of the lower end of the ejector.

The nipple 15^h is connected by a tube 17 to a nipple 17^a attached to a water-chamber 17^b in the hub of disk 4, as shown in Figs. 1 and 4, said water-chamber 17^b communicating with a water supply pipe 17^e, by means of a bore 17^c in the upper part of shaft 1, connected by means of a rotatable stuffing-box 17^d with pipe 17^e. By this means, water can be continually supplied to the ejector during its travel. As it is only necessary or desirable to supply the water to the saw during the cutting operations, the ejector outlet port 15^f is so located that it is normally closed, while the ejector is in elevated position, by the bore of the saw shank into which it fits; but just as or before the cutting operation begins, the ejector is partly depressed, by coming in contact with cam 16, so that port 15^f is uncovered, and water immediately flows into the saw, and continues to flow thereto during the cutting operation, see Fig. 9, supplying the water to the interior of the saw where it is most desirable to have it. The cam 16 is so proportioned that the ejector remains depressed during the entire cutting operation, and until after the blank is ejected, whereupon the ejector springs upward, and the flow of water is cut off.

The parts are so constructed and relatively located that the saw and clamp are separated, after the blank is cut, and when the clamp is fully lowered the saw passes over the mouth of a small chute 18, and at this time the ejector pushes the blank from the saw, and it drops into the chute and is delivered into any suitable receptacle. Below the shell-holders, and supported on the disk 3, as shown, is a broad skirt-flange 3^m upon which the shell waste is dropped, and carried around until it is swept off the flange by a blade 3ⁿ, located at a suitable point to direct the waste into a suitable receiver.

Operation: The operation of the machine will be clearly understood from the foregoing; but is briefly summarized as follows. The operator with a supply of uncut shells, stands or sits beside the machine at the point where the saws and holders are fully separated. As each holder comes up, the operator raises the clamp with one hand and places a shell on the bearing-member, and lowers the clamp thereon upon the part of the shell from which a blank is to be cut; the clamp strikes the pearl and comparatively flat side of the shell, while the convex side thereof rests on the bearing-member which automatically adjusts itself to the

curvature of the shell, and keeps its upper surface in close contact with the lower edge of the clamp-member, and practically perpendicular to the plane of the saw, no matter what the inclination of the under surface of the shell may be. All this is accomplished almost instantaneously, so that the movement of the parts is not retarded. The shell holder and shell move on, and are lifted by the cams, so as to bring the shell to the saw, which is rotated at a high speed, the saw working within the clamp-member which forms a saw guard and guide, so that the operator is not bothered by flying particles of shell.

On the upward movement of the holder the spring causes it to clamp the shell so forcibly that it will not be displaced by the action of the saw. As or before the saw contacts with the shell, the water is admitted into the saw, so that the cutting is effected with the least injury to the shell or saw; the cutting taking place as the holder and saw travel. When the blank is cut from the shell; the holder and saw are separated; then the blank is ejected from the saw into the chute, and the water cut off; and the parts travel on to the operator who readjusts the shell for another cut; or removes it if fully cut, and puts in a fresh shell. In the machine shown, a number of shells can be operated upon simultaneously. The shell-holder may be opened and closed either by raising and lowering the clamp-member or by lowering and raising the bearing-member, as is obvious. I prefer to raise and lower the clamp-member, and when thus using it the bearing-member can remain in its elevated position; and in such case if the operator desires to stop the cutting operation on any shell without stopping the machine he could do so by lowering the bearing-member on which such was supported. A cup 11ⁿ may be attached to the upper end of spindle 11, to catch any water which might overflow upwardly between the spindle and ejector rod during the time port 15^f is opened, and the amount of water supplied to each saw can be regulated by a valve of any suitable construction arranged in the length of pipe 17 as indicated at 17^a in the drawings.

Having thus described my invention what I claim as new and desire to secure by Letters Patent is:

1. A shell-holder comprising a tubular clamp-member, and a self-adjusting tiltable bearing-member between which members the shell is held.
2. A shell-holder for button blank cutting machines, comprising a self-adjusting oscillating-member, and an opposed tubular member.
3. A shell-holder for button blank cutting machines, consisting of a universally tiltable

- bearing-member adapted to adjust itself to the exterior contour of the shell; and a tubular clamp-member adapted to engage the inner surface of the shell and press the shell 5 securely against the bearing-member.
4. A shell-holder comprising an annular clamping-member—serrated on its biting edge—, and a tilttable bearing-member self-adjusting to inequalities of the shell, between which members the shell is clamped; means for separating said members, and means for normally closing them, substantially as described.
5. In combination, a cutting tool, a movable support, a self-adjusting bearing-member mounted on the support, devices for raising and lowering the support, and a clamp-member movable to and from the bearing-member independently of the support and also movable with the support, means for moving the support toward the tool and means for increasing the bite of the clamping-member as the support is moved.
6. In a button cutting machine, a shell-holder, comprising a tilttable bearing-member, means whereby the member is raised and lowered, a clamp-member movable with and also to and from the bearing-member, and means for separating the members.
7. In a button cutting machine, a work-holder, comprising a tilttable bearing-member, a cylinder supporting said member, and means for lowering and raising said cylinder; with a clamp-member movable with and also to and from the bearing-member.
8. A work-holder comprising a support, a revoluble cylinder thereon, cam devices whereby the cylinder is raised and lowered as rotated, a bearing-member supported by the cylinder, and a clamp-member movable to and from the bearing-member.
9. In a button cutting machine, the combination of a movable support, a revoluble cylinder thereon, cam devices for raising or lowering the cylinder as it is turned, a bearing-member mounted on the cylinder, and a clamp-member movable to and from the bearing member independently of the support and also movable with the support.
10. In a button blank cutting machine, the combination of a saw, a shell-holder in axial alinement therewith, comprising a clamp-member and an opposed co-acting self-adjusting tilttable member engaging the back 35 of the shell, means for causing said members to hold the shell, and means for causing the saw to operate on the shell while held by said holder.
11. In a button cutting machine, the combination of a saw, a shell-holder comprising a clamp-member adapted to hold the face of the shell in a plane perpendicular to the saw, and a yieldable self-adjusting bearing-member engaging the back of the shell, means 45 for opening and closing the holder, and means for causing the saw to operate on the work while held by said holder.
12. In a button cutting machine, the combination of a saw, a shell-holder comprising a self-adjusting bearing-member adapted to contact the exterior of the shell, a tubular clamping-member adapted to engage the interior of the shell and press it against the bearing-member, means for opening and closing the holder, and means for moving 70 the holder to and from the saw.
13. In a button cutting machine, the combination of a rotary spindle, a saw carried thereby, and a shell-holder opposite the saw spindle; with means for moving the holder toward the saw to enable it to cut blanks from the shell; means for increasing the bite of the holder on the shell as it reaches the saw, and means for supplying water to the interior of the saw during the cutting 75 operations.
14. The combination of a shell-holder comprising an adjustable bearing-member and a clamping member movable to and from the bearing-member and adapted to clamp the work thereagainst, and means for moving the holder bodily; with a saw in axial alinement with the work-holder, means for causing the saw to operate upon the shell presented thereto by said holder, and 80 means for supplying water internally to the saw during the cutting operation.
15. In a button blank cutting machine, the combination of a traveling series of shell-holders, each comprising a self-adjusting bearing-member and a clamping-member adapted to retain a shell; a similar series of rotatable tools opposite and traveling with the series of shell-holders, means for causing the tools to operate on the shells during part 85 of their travel, and to separate therefrom during the remainder of their travel; with means for supplying water internally to the saws during the cutting operation, and for ejecting the blank from the saws after the 95 cutting operation, substantially as described.
16. In a button blank cutting machine, the combination of a traveling series of shell-holders, each comprising a self-adjusting bearing-member and a tubular clamping-member adapted to retain a shell; and a similar series of rotatable saws opposite and traveling with the series of shell-holders; with means for moving the shell-holders to present the shells to the saws during part of 100 their travel, and to separate therefrom during the remainder of their travel; means for supplying water internally to the saws during the cutting operation, and means for 110 ejecting the blank from the saws after the cutting operation, substantially as described.
17. In a button cutting machine, the combination of a series of movable rods, a shell-holder carried by each rod comprising a self-adjusting bearing-member and a spring 115
18. In a button cutting machine, the combination of a series of movable rods, a shell-holder carried by each rod comprising a self-adjusting bearing-member and a spring 120
19. In a button cutting machine, the combination of a series of movable rods, a shell-holder carried by each rod comprising a self-adjusting bearing-member and a spring 125
20. In a button cutting machine, the combination of a series of movable rods, a shell-holder carried by each rod comprising a self-adjusting bearing-member and a spring 130

pressed clamp-member; a series of rotatable saws opposite the shell-holders and traveling therewith, means for rotating said saws during their travel, and cams for causing 5 the shell-holders to present the shells to the saws during part of their travel.

18. In a button cutting machine, the combination of a pair of rotatable disks, a series of movable rods carried by said disks, a 10 shell-holder carried by each rod comprising a self-adjusting bearing-member and a spring-pressed clamp-member; with a series of rotatable saws mounted on one disk opposite the shell-holder and traveling there- 15 with, means for rotating said saws during their travel, and cams for causing the shell-holders to present the shells to the saws during part of their travel.

19. In a button cutting machine, the combination of a series of movable rods, a shell- 20 holder carried by each rod comprising a self-adjusting bearing-member and a spring-pressed clamp-member; a series of rotatable saws opposite the shell-holders and traveling therewith, means for rotating said saws during 25 their travel, and cams for causing the shell-holders to present the shells to the saws during part of their travel; with means for introducing water into the saws during the 30 cutting operations, and means for ejecting blanks from the saws after the cutting operations, substantially as and for the purpose described.

20. In a button cutting machine, the combination of a rotary tubular saw, a tube in 35 said saw adapted to supply water to the interior of the saw, and a cam for automatically shifting the tube to admit water during the cutting operation, and to shut it off after 40 such operation.

21. In a button cutting machine, the combination of a rotary tubular saw, a hollow 45 rod in said saw adapted to conduct water to the interior of the saw, means for supplying water to said rod, and means for shifting the rod so as to close and open the water outlet.

22. In combination, a rotary tubular saw, 50 a blank ejecting rod, and means for actuating said rod to eject the blank from the saw after the cutting operation; with a water supply connected to said ejector rod whereby water is admitted to the saw during the cutting operation; said water supply being controlled by the movements of the rod.

23. In combination, a tubular saw, a hollow 55 ejector rod, a water supply connected with said rod, means for moving the rod so as to admit water into the saw during the cutting operation, and to eject the blank from the saw after the cutting operation, and to cut off the flow of water after the ejecting operation.

24. In a button cutting machine, the combination of a rotary spindle, a tubular saw 60

detachably attached thereto, a blank ejecting rod in said spindle, and means for actuating said rod to eject the blanks after the cutting operation; with a water supply connected to said ejector rod, whereby water is admitted to the saw during the cutting operation; said water supply being controlled by the longitudinal movement of the said rod, substantially as described. 70

25. In a button cutting machine, the combination of an adjustable sleeve, a rotatable spindle journaled therein, a tubular saw connected to said spindle, a hollow ejector rod in said spindle, a water supply connected with said rod, means for moving the rod so as to admit water into the saw during the cutting operation and to eject the blank from the saw after the cutting operation, and to cut off the flow of water after the ejecting operation, substantially as described. 75

26. In combination, a rotary spindle, a tubular saw detachably fitted to the end of said spindle, an ejector rod in said spindle adapted to eject blanks therefrom and whereby the saw may be ejected from the spindle 80 by an excessive movement of the ejector. 85

27. In a button cutting machine, the combination of a rotary spindle, a tubular saw having a shank fitted into the end of said spindle, an ejector rod in said spindle adapted to eject blanks therefrom and having a shoulder above the saw shank, whereby the saw may be ejected from the spindle by an excessive movement of the ejector. 95

28. In combination, a rotary spindle, a tubular saw fitted in the end of said spindle, a hollow ejector rod in said spindle provided with an outlet port in its lower end closed when the rod is in retracted position, a water supply connected with said ejector rod; 100 and means for actuating said rod at the proper times so as to open or close the outlet port; or to eject the blanks from the saw; or, by a further ejecting movement of the rod to force the saw from the spindle. 105

29. In a button cutting machine, the combination of a rotary spindle, a tubular saw fitted in the end of said spindle, a hollow ejector rod in said spindle provided with an outlet port in its lower end, closed when the rod is in highest position, a water supply connected with said ejector rod; and means for actuating said rod so as to open or close the outlet port; or to eject a blank from the saw; or to force the saw from the spindle, substantially as described. 110

30. In a button cutting machine, the combination of a rotary spindle, a tubular saw having a tapered shank, with a contracted bore fitted in the end of said spindle, a hollow ejector rod in said spindle provided with an outlet port in its lower end, closed by the bore of the saw when the rod is in highest position, a water supply connected with said ejector rod; and means for actuating 115

said rod so as to open or close the outlet port; or to eject a blank from the saw; or by a further ejecting movement of the rod to force the saw from the spindle, substantially as described.

31. A shell-holder for button blank cutting machines, comprising a tubular clamp-member, and an opposed tilttable bearing-member between which members the shell is held, a support for the bearing member, and ball bearings supporting said bearing-member on said support.

32. A shell-holder for button blank cutting machines, comprising an annular serrated clamp-member, an opposed tilttable bearing-member between which members the shell is held, a support for the bearing member, and ball-bearings sustaining said bearing-member on its support; with means for normally closing said members, and means for separating them, substantially as described.

33. In a button cutting machine, a work-holder comprising a tilttable self-adjustable

bearing-member, a support therefor, cam devices for raising and lowering said support, a clamp-member also mounted on said support and movable to and from and with the bearing-member, and manually operated means for separating the said members.

34. In a button cutting machine, a work-holder comprising a tilttable self-adjusting bearing-member, a support therefor, cam devices for raising and lowering said support, a clamp-member on said support and movable to and from and with the bearing-member, manually operated means for separating the members, and means for increasing the bite of the clamping-member on the bearing-member as the support is raised.
